DESIGN FOR A DRESS

Herbert M. Harris, New York, N. Y.

Application August 13, 1940, Serial No. 94,404

Term of patent 3½ years

To all whom it may concern:

Be it known that I, Herbert M. Harris, a citizen of the United States of America, residing in New York, county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the princess dress disclosed of the specific lace trimmed collar member in association with the floral button members on the front portion and the half belt, all as shown.

I claim:

The ornamental design for a dress, as shown and described.

HERBERT M. HARRIS.
